(57) **CLAIM**

The ornamental design for a television receiver, as shown and described.

DESCRIPTION

1. Television receiver

1.1 : Perspective

1.2 : Front

1.3 : Back

1.4 : Left

1.5 : Right

1.6 : Top

1.7 : Bottom

1.8 : Enlarged

1.9 : Reference view

The evenly-spaced broken lines shown in 1.1-1.6, 1.8 and 1.9 of the television receiver depict unclaimed portions of the television receiver and form no part of the claimed design.

The evenly-spaced broken lines shown in 1.9 behind and around the television receiver are included for the purpose of illustrating environment and form no part of the claimed design.

(Continued)

The dash-dot broken line portions of **1.1** and **1.8** are included to show partially enlarged views only and form no part of the claimed design.

1 Claim, 6 Drawing Sheets
